LOOSE LEAF BINDER

Filed June 4, 1928

UNITED STATES PATENT OFFICE

ADOLPH G. LOTTER, OF MILWAUKEE, WISCONSIN, ASSIGNEE, BY MESNE ASSIGNMENTS, TO STATIONERS LOOSE LEAF CO., OF MILWAUKEE, WISCONSIN, A CORPORATION OF WISCONSIN

LOOSE LEAF BINDER

Application filed June 4, 1928. Serial No. 282,725.

This invention relates to certain new and useful improvements in loose leaf binders particularly of the type having two binder heads, from one of which flexible posts or chains are extensible to have their outer free ends fixed to the other head so that upon the operation of suitable take-up mechanism, a retaining pressure is applied to a body of leaves inserted between the binder heads.

It is an object of this invention to provide an improved binder structure whereby sheets having round apertures may be used in lieu of the slotted apertures heretofore used and in which the uppermost binder head may be instantly detached from the chains or posts to permit the ready removal or addition of sheets.

Another object of this invention resides in the provision of an improved loose leaf binder of the character described having a novel bridge plate provided with posts for assisting in holding the sheets in the binder when the uppermost head is removed and to facilitate the removal of any number of the uppermost sheets or the insertion or addition of sheets.

A more specific object of this invention resides in the provision of an improved binder of the character described in which the adjustable flexible posts have grooves or recesses in their outer ends adapted to be passed into the uppermost binder head for engagement with a readily operable latch mechanism carried thereby.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have

so far devised for the practical application of the principles thereof, and in which:

Figure 1 is a side view, partly in elevation and partly in section, of the binder heads of a loose leaf binder embodying my invention;

Figure 2 is a view, partly in section and partly in elevation, taken through Figure 1 on the plane of the line 2—2;

Figure 3 is an enlarged, fragmentary, sectional view, taken through the upper binder head on the plane of the line 3—3 of Figure 1; and

Figure 4 is a transverse, sectional view, taken through the binder heads on the plane 65 of the line 4—4 of Figure 1.

Referring now more particularly to the accompanying drawings, in which like numerals designate like parts throughout the several views, 5 and 6 designate the upper and lower binder heads, respectively, of a loose leaf binder between which a body of leaves 7 is adapted to be clamped and protected by cover members 8 hinged to the binder heads, as at 9. The binder heads are of 70 tubular construction, preferably formed from sheet-metal or tubing of approximately rectangular shape in transverse section and have their ends closed by caps 10 which provide the means for mounting the covers 8.

The lower binder head preferably has a right and left threaded screw-shaft 11 transversely journaled therein with nut members 12 mounted thereon to provide 85 means for extending and retracting a pair of flexible post sections 13 which pass into the binder head at points slightly spaced from each end through guide ways 14 to extensibly lie therein, the screw-shaft 11 90 being actuated by a removable key 15 in the conventional manner. The free end portions of the flexible posts have provision for adding sections 16 and in the endmost section 16 is threaded an end piece 17 having 95 a locking groove 18 for the purpose later described.

The extreme free ends of the flexible posts, formed by the end pieces 17, are passed into the uppermost binder head 100

through apertures 19 in its inner wall 20 in register with the guide ways 14 to engage in socket members 21 fixed to the top wall of the head. The sockets 21 cooperate with guides or spacers 22 struck from the sides of a slide bar 23 to slidably position the bar in the plane of the grooves 18 when the ends of the flexible posts are engaged within the sockets 21. The slide bar 23 has a pair of medial elongated openings 24 for the purpose later described and a pair of key-hole slots 25, the large portions 26 of which register with the openings 19 and the sockets 21 and are of a size 15 to receive the head 17 of the posts, and the smaller portions 27 being of a size to snugly engage the reduced portion of the end members 17 at their grooves 18.

One end 28 of the slide bar is reduced in width and passes through an aperture 29 in the adjacent end cap 10 and is bent downwardly, as at 30, to provide a finger-engaging member for the convenient actuation of the bar in the upper binder head. When the upper binder head is to be attached to the posts 13, the finger-engaging piece 30 of the slide bar is engaged to move the bar to the right with reference to Figures 1 and 2, registering the enlarged portion 26 of the key-hole slots with the apertures 19 in the bottom wall of the upper binder head, to permit the insertion of the end members 17 in the sockets 21 with their recesses 18 in alignment with the smaller portions of the key-hole slots. The slide bar is then moved to the left with reference to Figures 1 and 2 to engage the smaller portions 27 of the key-hole slots with recesses 18 of the posts.

The body of leaves are retained on the lower binder head in the proper stacked position when the upper binder head is removed by rigid posts 31 fixed medially thereto, as at 32, and having their outer ends 33 adapted to be passed into the upper binder head, when in place, through apertures 34, the posts 31 having provision for the addition of sections thereto. The elongated openings 24 in the bar 23 register 50 with the openings 34 to permit the posts to pass therethrough without interfering with the operation of the bar.

The leaves are further held in their proper stacked position when the upper binder head is removed and particularly when the body of leaves is thicker than the length of the posts 33, by inverted posts 35 carried by a bridge bar 36 adapted to be engaged with the top-most sheets of the body and 60 having apertures registering with the apertures 19 and 34 of the inner wall of the upper binder and through which the flexible posts 13 and the posts 31 pass. The bridge bar also assists in maintaining the top-most sheets of the body in proper align-

ment in the event they are removed to permit the insertion of other sheets, as will be readily apparent; and further assists posts 31 in retaining the leaves in proper alignment for the engagement of the top binder head with the flexible posts. 70

From the foregoing description, taken in connection with the accompanying drawing, it will be readily apparent to those skilled in the art to which an invention of the character described appertains, that I provide a novel and improved binder head in which one of the heads may be easily removed to permit the removal or insertion of additional sheets and which may be firmly connected with the flexible posts to permit the application of any desired tension thereon. 75

What I claim as my invention is:

1. In a loose leaf binder, a pair of binder heads, a substantially flexible post member extensibly connected with one head and adapted to be passed into the other, means concealed within said other binder head for readily detachably connecting the same with the end of the post passed therein, a rigid binder post connected with the first binder head to maintain a body of leaves in alignment thereon when the second binder head is removed, a bridge bar adapted to engage the top-most leaves, and a binder post rigid therewith and adapted to be passed through the leaves in a direction opposite to the first mentioned rigid post. 90

2. In a loose leaf binder, a pair of binder heads, a substantially flexible post member extensibly connected with one head and adapted to be passed into the other, means concealed within said other binder head for readily detachably connecting the same with the end of the binder post passed therein, a bridge bar adapted to engage the topmost of a body of leaves adapted to be secured between the binder heads, and a binder post rigid therewith and adapted to be passed through the leaves. 100

3. In a loose leaf binder, a tubular binder head having an aperture in one wall through which one end of a post extends into the binder head, a substantially cup-shaped member stamped from bendable metal carried by the opposite wall of the binder head in alignment with the aperture, a slide bar mounted between the cup-shaped member and the apertured wall adapted to be engaged with the post member to detachably connect the said head therewith, means carried by the slide bar and engaging the apertured wall to cooperate with the cup-shaped member in maintaining the slide bar in its proper plane of movement. 110

4. In a loose leaf binder, a tubular binder head having an aperture in one wall adapted to receive a binder post, a substantially cup-shaped member stamped from bendable metal secured to the opposite wall of the 120

binder head in alignment with the aperture and adapted to receive the end of the post extended into the binder head, a slide bar mounted between the cup-shaped member and the apertured wall adapted to engage with the post member to detachably connect the head therewith, said slide bar engaging the cup-shaped member, and spacing means struck from the slide bar and engaging the apertured wall to cooperate with the cup-shaped member in maintaining the slide bar in its proper plane of movement.

5. In a loose leaf binder, a tubular binder head having an aperture in one wall, a binder post adapted to have one end extended into the binder head, said end of the post having an annular groove, a substantially cup-shaped member carried by the opposite wall of the binder head in alignment with the aperture and adapted to receive the extreme end of the post, a slide bar mounted between the cup-shaped member and the apertured wall and having a key-hole slot engageable with the post annular groove to detachably connect the head with the post, one side of the slide bar engaging the cup-shaped member, and flanges struck from the slide bar adjacent the key-hole slot and engaging the apertured wall to space the slide bar therefrom and cooperate with the cup-shaped member in maintaining the slide bar in proper alignment with the annular groove in the post.

In testimony whereof I have hereunto affixed my signature.

ADOLPH G. LOTTER.
